UNITED STATES PATENT OFFICE.

HENRY LITTLETON, OF MARICOPA, CALIFORNIA.

BURNER.

1,014,496.

Specification of Letters Patent.

Patented Jan. 9, 1912.

Application filed August 17, 1911. Serial No. 644,517.

To all whom it may concern:

Be it known that I, HENRY LITTLETON, a citizen of the United States, residing at Maricopa, in the county of Kern, State of California, have invented certain new and useful Improvements in Burners; and I do hereby declare the following to be a full, clear, and exact description of the invention, such as will enable others skilled in the art 10 to which it appertains to make and use the same.

This invention relates to spray burners and has for an object to provide an L-shaped mixing chamber which will promote a swirling motion of the oil and injected steam so that a thorough mixing of both is effected.

A further object of the invention is to provide a burner having a supplemental fuel outlet so arranged that flame from the 20 burning of the escaping fuel envelops the burner and intensely heats the same.

With the above objects in view the invention consists in certain novel details of construction and combination of parts herein- 25 after fully described and claimed, it being understood that various modifications may be made in the minor details of construction within the scope of the appended claims.

In the accompanying drawings forming 30 part of this specification:—Figure 1 is a side elevation of a burner embodying my improvements. Fig. 2 is an end elevation of the burner. Fig. 3 is a longitudinal sectional view of the burner. Fig. 4 is a detail 35 perspective view of the steam pipe discharge end. Fig. 5 is a side elevation with parts in section of a modified form of the device.

Referring now to the drawings in which like characters of reference designate similar parts, 10 designates a T coupling, the opposite ends of the alined branches of which are closed by reducers 11 and 12, the reducer 11 having an axial nipple 13 of less bore than the axial nipple 14 of the reducer 45 12. Threaded into the lateral branch of the T coupling is an L coupling 15 which communicates with an oil supply pipe 16, the flow of oil through this pipe being controlled by a valve 17 of any preferred construction.

Threaded in the nipple 13 of the reducer 11 is a jet pipe 18 which extends through and is of considerably greater length than the alined branches of the T coupling. The 50 threaded end of the pipe extends outwardly

beyond the nipple and is connected to any suitable steam supply, preferably the boiler under which the burner is desired to operate. The discharge end of the jet pipe is reduced and formed with a substantially square 60 nozzle 19.

Threaded into the nipple 14 of the reducer 12 is one end of a pipe 20, the opposite end of this pipe being threaded into one end of an L shaped coupling 21 the opposite end 65 of which coupling is closed by a plug 22. This coupling forms a mixing chamber, and it will be noted that the discharge end of the jet pipe is substantially flush with and extends axially into the lower end of the 70 chamber. The jet of steam from the jet pipe mixes with the oil flowing through the pipe 20, and the mixture being urged forward under the pressure of the injected steam, will impinge against the curved wall 75 of the chamber which confronts the discharge end of the jet pipe and be deflected upwardly against the plug 22, and from thence will be deflected back again toward the jet pipe. In this manner a swirling 80 movement of the mixture is promoted and a complete mixing of the steam with the oil effected.

Formed in the advance wall of the mixing chamber is a downwardly opening trans- 85 verse slot 23, the inner end of this slot confronting and being disposed centrally relatively to the discharge end of the jet pipe as clearly shown in Fig. 3. Through this slot the mixture will be discharged and 90 will be directed in a substantially flat sheet underneath the boiler to which the burner is applied. Formed in the wall of the mixing chamber below the slot is a circular opening 95 24 of relatively small diameter. A portion of the mixture will escape downwardly through this opening, and the flame from the burning of the mixture will rise and envelop the entire mixing chamber causing the contents of the latter to be heated and 100 the oil rendered more fluid so that the thorough mechanical mixing of the oil and steam is promoted.

It is to be understood that to assure best working of the burner, it should be mounted 105 in upright position, that is, with the plug 22 disposed at the highest point in the device. When so mounted, the rising of the flame from the opening 24 will be assured at all times.

In order to drain the device a short length of pipe 25 is threaded into one side of the T coupling, and to the outer end of this pipe is attached an L coupling 26 to which is connected a pipe 27, the discharge of oil through this pipe being controlled by a valve 28 of any preferred construction arranged in the bore of the pipe.

It will be here stated that the difference 10 between the interior diameter of the pipe 20 and jet pipe 18 is preferably but one sixteenth of an inch, practice having demonstrated that this space effects the most efficient working of the device.

15 In Fig. 5 the parts of the burner are identical with the parts above described with the exception that interposed between the pipe 20 and mixing chamber 21 is disposed a stand pipe 29 having an elbow connection 30 with the pipe 20 and an elbow connection 31 with a horizontally disposed stub pipe 32 which in turn is connected to the above described mixing chamber 21. The utility of this intermediate stand pipe is that 25 when a small amount of oil is designed to be used, the steam being confined for a greater length of time in the mixing chamber or in other words in the stand pipe, will thoroughly mix with the small quantity of oil before the discharge of the oil and furthermore this stand pipe connection permits of the device being used in high furnaces 30 where it is impossible to use the preferred form above described.

What is claimed, is:—

1. A burner including a substantially L shaped mixing chamber having a closed upper end, an oil supply pipe communicating with the open lower end of said chamber, a steam jet pipe within said oil pipe 40 extending into said chamber, the outer wall of said chamber being formed with an elongated transverse slot which confronts the discharge end of said jet pipe, and the lower wall of said chamber being formed with a 45 downwardly opening orifice of relatively small diameter.

2. A burner including an oil supply pipe, a steam jet pipe arranged within said oil pipe, an elbow carried by said oil pipe, a 50 stand pipe carried by said elbow, an elbow carried at the upper end of said stand pipe, and a substantially L-shaped mixing chamber having a lower open end communicating with the last named elbow, and having a 55 closed upper end, the outer wall of said chamber being formed with a transverse slot, and further being formed with an opening of substantially small diameter intermediate said slot and the lower open end of 60 said chamber.

In testimony whereof, I affix my signature, in presence of two witnesses.

HENRY LITTLETON.
